COMBINED BAR AND ELECTRIC MODEL CAR RACE TRACK

Irene Weiss and Harry M. Weiss, both of 923 Eden Ave.,
San Jose, Calif. 95117

Filed Oct. 9, 1964, Ser. No. 82,116

Term of patent 14 years

(Cl. D34—5)

FIGURE 1 is a top plan view of a combined bar and electric model car race track showing our new design; and FIGURE 2 is a side elevational view thereof.

The characteristic feature of our design resides in the combination on the bar of a planar surface surrounding a banked inner region in which is located a plurality of slots for electric model cars, all as shown.

We claim:

The ornamental design for a combined bar and electric model car race track, as shown and described.
